(57) **CLAIM**

The ornamental design for a wash system for 3D-printed parts, as shown and described.

DESCRIPTION

FIG. 1 illustrates a front-perspective view of a wash system for 3D-printed parts;

FIG. 2 illustrates a back-perspective view thereof;

FIG. 3 illustrates front view thereof;

FIG. 4 illustrates a top view thereof;

FIG. 5 illustrates a bottom view thereof;

FIG. 6 illustrates a back view thereof;

FIG. 7 illustrates a right-side view thereof;

FIG. 8 illustrates a left-side view thereof;

FIG. 9 illustrates a front-perspective view, showing a lid-opened state thereof;

FIG. 10 illustrates a back-perspective view, showing a lid-opened state thereof; and

FIG. 11 illustrates front view, showing a lid-opened state thereof;

FIG. 12 illustrates a top view, showing a lid-opened state thereof;

FIG. 13 illustrates a bottom view, showing a lid-opened state thereof;

FIG. 14 illustrates a back view, showing a lid-opened state thereof;

FIG. 15 illustrates a right-side view, showing a lid-opened state thereof; and,

FIG. 16 illustrates a left-side view, showing a lid-opened state thereof.

The broken lines in the figures illustrate portions of the wash system for 3D-printed parts that form no part of the claimed design.

1 Claim, 16 Drawing Sheets
